Howard E. Thompson
ATTORNEY

UNITED STATES PATENT OFFICE

ISAAC MARINSKY, OF PROVIDENCE, RHODE ISLAND

GLOVE

Application filed March 31, 1928. Serial No. 266,142.

This invention relates to gloves or any other class of hand covering and particularly to the provision of a pocket in the glove in which change and other small articles may be stored for convenient accessibility; and the object of the invention is to provide an improved pocket construction consisting of relatively movable parts with means for coupling said parts together to close the open end of the pocket, and said parts permitting of the formation of a comparatively large opening controlling admission to the pocket to facilitate the easy removal of the articles contained in the pocket and also the placement of the articles therein; a further object being to provide a pocket of the class described comprising overlapping wall members, both of which engage one part of a fastening device in coupling said members together to close a pocket opening; a further object being to provide a pocket of the class described, at least one part of which is formed integral with one of the glove forming members and which may be formed from two of said members by the use of an additional part or section; and with these and other objects in view, the invention consists in a glove of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a plan view of the palm portion of a glove showing one form of my improved pocket construction.

Fig. 2 is a view similar to Fig. 1 but showing a pocket opened.

Fig. 3 is a section on the line 3—3 of Fig. 1.

Fig. 4 is a view similar to Fig. 2 but showing a modified form of pocket in a partially open position; and,

Fig. 5 is a view similar to Fig. 2 but showing another modification.

In the several figures of the accompanying drawing, 10 represents the main body portion

of the glove from which the four fingers, palm and wrist portion of the glove are formed, and 11 the thumb forming portion. The thumb forming portion extends to the stitched side 10^a of the glove to form a palm portion 11^a. It will be understood that the glove structure comprising the parts 10 and 11 may be made in the usual or any desired manner, and may be of any preferred type of hand covering such as mittens, driving gloves, dress gloves, work gloves and the like.

In the structure shown in Figs. 1 to 3 inclusive, the palm portion 10^b of the glove is cut out on the lines 12 from the base of the finger portion and a part of the thumb portion to a point adjacent the stitched side 10^a as seen at 12^a to form thereof a flap 13 having one part 14 of a snap fastening device. In this construction, an insert piece 15 is arranged upon the thumb part 11 and is stitched thereto on the line of stitching 15^a and extends upwardly to the base of the finger portion of the glove and is stitched thereto as is also the palm portion 11^a of the glove on the line of stitching 16. The free edge of the insert 15 forms a flap 17 which lies under the palm portion 10^b or the flap 13 thereof as clearly seen in Figs. 1 and 2 of the drawing, and this insert has an aperture 18 which passes over a knob of the other part 19 of the snap fastener so that when the two parts 14 and 19 are brought together with the flaps 13 and 17 in the position shown in Fig. 1, the flap 17 is secured in position closing the pocket 20 formed within and between the parts 10^b, 15 and 11^a.

The pocket is shown in its open position in Fig. 2, with the flaps 13 and 17 folded backwardly, thus providing a large opening, permitting the placement of two or more fingers of the hand into the pocket 20 to facilitate the removal of articles therefrom. It will be understood that the lower end of the palm portion 11^a is stitched to the glove 10 as indicated by the line of stitching 21, and thus the palm portion 11^a becomes an integral structure with the body 10 of the glove proper in addition to the thumb portion 11.

In the construction shown in Fig. 4 of the drawing, the palm portion 11^a of the part 11 is stitched to the glove part 10 in addition to the stitching at 10^a by stitchings 22 arranged adjacent the base of the finger portion of the glove, and stitchings 23 at the wrist portion of the glove, the latter closing the lower end of the pocket 24 formed within and between the palm portion 11^a and the palm portion 10^b of the part 10. In this construction, the palm portion 10^b is free at its side edge 25, the stitching shown being merely for the purpose of forming a reinforced edging, and this free edge 25 is cut angularly on the line 26 toward the center of the palm portion of the glove to form of the palm portion 10^b, two flaps 27 and 28. The flap 28 is shown turned backwardly and is provided with one part 29 of a snap fastener adapted to engage the other part 30 secured to the palm portion 11^a of the thumb part 11 of the glove. In this construction, an extension piece 27^a is attached to the flap 27 and lies under the flap 28 and is provided with an aperture 31 to pass over the knob of the snap fastener 30 so as to secure both flaps 27 and 28 in position when the part 29 of the snap fastener is brought into engagement with the part 30. This also closes the pocket 24 as will be apparent. The extension piece 27^a of course constitutes part of the flap 27 and is also foldable backwardly to provide a large opening controlling admission to the pocket 24, which in this construction is arranged between the parts 10^b and 11^a.

In the construction shown in Fig. 5 of the drawing, the palm portion 10^b of the glove has free side portions 32 and 33 and a free end portion 34 forming a substantially tongue-like member provided at its free end with the knob member 35 of a snap fastener. In this construction, two insert pieces 36 and 37 are arranged between the palm portions 10^b and 11^a and are secured respectively to the edges 32—33 of the palm portion 10^b and to the palm portion 10^a as seen at 38 and 39 respectively, thus forming the pocket 40. The insert pieces 36 and 37 are preferably folded centrally to collapse the same and also to form a comparatively large opening to the pocket 40, which in this construction is arranged between the parts 10^b—11^a and the insert pieces 36 and 37. I also provide the closure flap 42 which constitutes an extension of the wrist portion of the glove or the part 10 thereof. This flap carries the other part 41 of the snap fastener which engages the part 35 in closing the pocket 40.

The distinctive feature of the several forms of construction above described resides in providing a comparatively large opening giving access to the pocket of the glove, facilitating the easy placement of articles into said pocket and the removal of articles therefrom. While these pockets are preferably

arranged in the palm portion of the glove and are opened in the direction disclosed, it will be understood that the same may be located on any part of the glove structure and may open in any desired direction to suit the particular type of glove as well as the specific use of the pocket.

Various other changes in and modifications of the construction herein shown and described may be made within the scope of the appended claims without departing from the spirit of my invention or sacrificing its advantages.

Having fully described my invention, what I claim as new and desire to secure by Letters Patent, is:—

1. A glove of the class described fashioned from glove forming parts, one of which constitutes the main body part and having a thumb opening at one side and being stitched at the opposite side in forming said part, and the other a thumb forming part arranged in the thumb opening of the first named part and stitched thereto, both of said parts having integral palm portions, the palm portion of the thumb part extending to the stitched side edge of the main body part and being secured thereto by side stitchings and by other stitchings arranged at the base of the finger portions of the first named part to form within and between said palm portions a pocket opening outwardly through the palm portion of the glove, and means cooperating with said palm portions for forming a comparatively large open end to said pocket.

2. A glove of the class described fashioned from glove forming parts, one of which constitutes the main body part and having a thumb opening at one side and being stitched at the opposite side in forming said part, and the other a thumb forming part arranged in the thumb opening of the first named part and stitched thereto, both of said parts having integral palm portions, the palm portion of the thumb part extending to the stitched side edge of the main body part and being secured thereto by side stitchings and by other stitchings arranged at the base of the finger portions of the first named part to form within and between said palm portions a pocket opening outwardly through the palm portion of the glove, means cooperating with said palm portions for forming a comparatively large open end to said pocket, said last named means overlapping one of said palm portions, and means for closing the open end of the pocket.

3. A glove of the class described fashioned from glove forming parts, one of which constitutes the main body part and comprises palm, wrist, back and finger portions having a thumb opening arranged between the back and palm portions at one side of said part

and being stitched together along the opposite side edge thereof and around said finger portions, another part of the glove constituting the thumb part arranged within the thumb opening of the first named part and stitched thereto and including a palm portion extending and secured to the first named part at the base of the finger portions, the palm portions of both of said parts overlapping to form a pocket opening outwardly through the palm of the glove, the palm portion of the first named part having a free side edge extending longitudinally of the glove to form thereof a flap controlling admission to said pocket, and another glove part attached to one of the first named parts at the palm portion thereof to cooperate with the palm portions of said first named parts to form a comparatively large open end to 20 said pocket.

In testimony that I claim the foregoing as my invention I have signed my name this 28th day of March, 1928.

ISAAC MARINSKY.
